(57) **CLAIM**

The ornamental design for a case with multiple compartments, as shown and described.

DESCRIPTION

FIG. 1 is a top front perspective view of a case with multiple compartments, showing my new design;

FIG. 2 is a bottom front perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right-side elevation view thereof; and,

FIG. 8 is a left-side elevation view thereof.

The broken lines shown in the drawings depict portions of the article that form no part of the claimed design.

The broken lines shown in the drawings do not depict stitching, fold lines, or any portion of the claimed design.

1 Claim, 4 Drawing Sheets
